(57) **CLAIM**

(21) Appl. No.: **29/255,872**

The ornamental design for a knee grip cover for motorcycles, as shown and described.

(22) Filed: **Mar. 13, 2006**

DESCRIPTION

(30) **Foreign Application Priority Data**

Sep. 14, 2005 (JP) 2005-026531

FIG. 1 is a front elevational view of a knee grip cover for motorcycles showing our new design;

(51) **LOC (8) Cl.** **12-11**

FIG. 2 is a rear elevational view thereof;

(52) **U.S. Cl.** **D12/114**

FIG. 3 is a left side elevational view thereof;

(58) **Field of Classification Search** D12/110,

FIG. 4 is a right side elevational view thereof;

D12/114, 126, 186; 280/288.4, 304.3, 304.4;
180/219; 296/78.1, 193.01, 193.05

FIG. 5 is a top plan view thereof;

See application file for complete search history.

FIG. 6 is a bottom plan view thereof;

(56) **References Cited**

FIG. 7 is a perspective view thereof; and,

U.S. PATENT DOCUMENTS

FIG. 8 is a reference view of the knee grip cover for motorcycles from the right side of a motorcycle, shown on a reduced scale and in position of use.
